UNITED STATES PATENT OFFICE.

WILLIAM N. HENSLEY, OF COLUMBUS, NEBRASKA.

CAR-COUPING.

SPECIFICATION forming part of Letters Patent No. 740,013, dated September 29, 1903.

Application filed July 28, 1903. Serial No. 167,334. (No model.)

To all whom it may concern:

Be it known that I, WILLIAM N. HENSLEY, of Columbus, in the county of Platte and State of Nebraska, have invented a certain new and useful Improvement in Car-Couplers; and I do hereby declare that the following is a full, clear, and exact description thereof, reference being had to the accompanying drawings, in which—

- 10 Figure 1 is a perspective view of a car-coupler embodying my invention; Fig. 2, a like view of a portion of the draw-head, the jaw being removed; and Fig. 3 is a vertical cross-section of the coupler as shown in Fig. 1.
- 15 My invention relates to car-couplers of the twin-jaw type in which a spring is provided for automatically throwing open the jaw or knuckle to place the same in position for coupling the cars to avoid the danger of breaking the jaw in coupling, which is likely to occur should the jaw be left in a closed position, and to remove the necessity of the trainman, at the jeopardy of life or limb, going between the cars to open the jaw to position
- 25 for coupling.

The object of my invention is to provide a coupler of the class in question in which a most simple form of spring can be used, one that may be easily placed in and removed from position in the draw-head when necessary and which will be free from likelihood of breakage or derangement from use; and to these ends my invention consists in the car-coupler having the construction substantially as hereinafter specified and claimed.

In making my present invention I have adapted it to the car-coupler which forms the subject of my United States Patent No. 711,496, October 21, 1902, and I illustrate and shall describe such invention in connection with that car-coupler, premising, however, that I do not limit myself to the employment of my invention with that particular construction of car-coupler, as it is adapted for use with all car-couplers of the twin-jaw type.

In the drawings, A designates the draw-head, and B the pivoted jaw or knuckle, the jaw or knuckle having, as usual, an inward extension or tail. The knuckle-locking bar C and the means for operating the latter are the same in construction as in the coupler of my before-mentioned patent, and therefore

they need not be described, as the same are fully shown and described in said patent.

Extending down between the tail of the 55 knuckle and the adjacent side of the draw-head is a spring D, which consists of a strip or plate that when free from restraint curves outward and downward away from the wall of the draw-head, its lower end being free 60 and bearing against the knuckle tail or extension in such manner as to operate to swing the knuckle into an open position, and the upper portion of said spring being passed through a vertical slot or opening in the top of 65 the draw-head, and its upper end being curved into a hook shape that catches over a lug or projection on the upper side of the draw-head and the spring thereby being secured in position. The lug is reduced in thickness 70 toward its bottom, and the hook on the spring is shaped to conform thereto, it therefore engaging with the lug, so as to securely retain the spring in place without the employment of bolts or other fastening devices. When 75 the knuckle is in a closed or coupling position, its tail presses the spring substantially flat against the adjacent side of the draw-head. On releasing the knuckle from the locking-bar C, which is done by operating the 80 operating-lever from the side of the car, the spring will act to throw the knuckle to an open position.

It will be seen that the form of spring which I employ, which is possible because of the position it has with reference to the knuckle, it extending parallel with the knuckle-axis, is one that is free from any sharp bends or turns, which in the operation of the spring would be specially subject to strains, and 90 therefore likely to result in the breakage of the spring, that the spring can be placed in and removed from position with absolutely no necessity of removing the knuckle or any other part of the coupler, and that it is so 95 housed or protected as to be free from possibility of derangement by the presence of any objects that, if it were in an exposed position, might accidentally be lodged or get in position to hinder its action.

Having thus described my invention, what I claim is—

1. In a car-coupler, the combination of a draw-head, a knuckle, and a spring consist-

ing of a plate or strip that extends parallel with the axis of the knuckle and lies between a part thereof and the draw-head.

2. In a car-coupler, the combination of a draw-head, a knuckle, and a spring consisting of a strip or plate that extends from the top of the draw-head downward between the side of the draw-head and a part of the knuckle, its lower end being free and bearing ²⁰ against said part of the knuckle.

3. In a car-coupler, the combination of a draw-head, a knuckle, and a spring consisting of a strip or plate that extends through a slot or opening in the top of the draw-head ²⁵ downward in the latter between the side of the same and a part of the knuckle, its lower

end being free and engaging said part, and its upper end being secured to the top of the draw-head.

4. In a car-coupler, the combination of a draw-head, a knuckle, and a spring consisting of a strip or plate that has a hook on one end and a lug on the draw-head that is reduced in thickness toward one side and is engaged by the hook. ²⁵

In testimony that I claim the foregoing I have hereunto set my hand.

WILLIAM N. HENSLEY.
